MECHANICAL PENCIL

Hugo S. Hasselquist, Oak Park, Ill., assignor to
 Joseph Dixon Crucible Company, Jersey City,
 N. J., a corporation of New Jersey

Application January 19, 1944, Serial No. 518,825

10 Claims. (Cl. 120—18)

1

This invention relates to mechanical pencils of the propel, retract type.

The invention has for its salient object to provide a pencil that is simple, practical and rugged in construction, comprises a minimum number of parts, is economical to manufacture, efficient in operation, and is so constructed as to materially reduce the amount of metal and number of metal parts required for its manufacture.

Another object of the invention is to provide a pencil of the character described with a new and improved clutch and ejector assembly so constructed and so mounted that the clutch will not become fractured or distorted in use.

Another object of the invention is to provide a clutch and ejector assembly so constructed and arranged that the ejector will always be properly centered in the clutch.

Another object of the invention is to provide a clutch and ejector assembly so constructed and arranged that the ejector controls the positioning of the clutch and prevents rotation thereof without necessitating coaction between the clutch and channel.

Another object of the invention is to provide means for frictionally retarding the retraction of the clutch.

Another object of the invention is to provide a novel, efficient, and easily assembled mounting for the tip in the barrel.

Another object of the invention is to provide a novel, efficient, and easily assembled mounting for the spiral tube and tip in the front end of the barrel.

Another object of the invention is to provide a simple and efficient spiral tube mounting and a mounting constructed to frictionally engage and retard or brake rotation of the magazine or body member.

Another object of the invention is to provide a magazine or body member with a channel member so mounted therein as to permit a frictional slippage between the magazine and channel member.

Further objects of the invention will appear from the following specification taken in connection with the drawings which form a part of this application and in which

Fig. 1 is a longitudinal sectional elevation of a pencil constructed in accordance with the invention, the clutch and ejector being illustrated at the rear end of the barrel or in their initial feeding positions;

Fig. 2 is a view similar to Fig. 1 but illustrating

the clutch and ejector at the extreme end of the feeding and ejecting positions thereof;

Fig. 3 is a transverse sectional elevation taken substantially on line 3—3 of Fig. 2, looking in the direction of the arrows;

Fig. 4 is a fragmentary sectional elevation illustrating the front end of the barrel and the manner of assembling the tip and spiral therein;

Fig. 5 is an enlarged transverse sectional elevation taken substantially on line 5—5 of Fig. 2, looking in the direction of the arrows;

Fig. 6 is a transverse sectional elevation taken substantially on line 6—6 of Fig. 1, looking in the direction of the arrows;

Fig. 7 is a transverse sectional elevation taken substantially on line 7—7 of Fig. 1, looking in the direction of the arrows;

Fig. 8 is an elevation, partly in section, of the magazine, illustrating the manner of assembling the channel tube in the magazine;

Fig. 9 is a side elevation of the clutch and ejector;

Fig. 10 is a top plan view of the structure shown in Fig. 9; and

Fig. 11 is a sectional elevation showing the rear or cap end of the pencil shown in Figs. 1 and 2.

The invention briefly described consists of a mechanical pencil comprising a barrel and a body member which, as illustrated, also consists of a magazine having longitudinal grooves in its outer periphery for storing leads. The magazine is rotatably mounted in the barrel but has a cap secured thereto at the rear end thereof by means of which the magazine can be rotated.

A spiral tube or a tube having a spiral slot extending throughout the length thereof is fixedly secured at its front end in a tapered member or sleeve which is also used to expand the rear end of the tip into frictionally tight engagement with the front end of the barrel. The rear end of the spiral tube has mounted thereon means such as a disk or washer and the spiral is stretched between the fixed forward end thereof and the rear end so

that the washer frictionally engages the rear end of the magazine or body member.

A clutch tube is mounted in the spiral and is provided with a lug which extends into the spiral slot. The clutch tube houses an ejector which projects through a longitudinal slot in the clutch tube and has an elongated rearwardly extending portion which is disposed in a channel formed in the channel tube secured in the magazine or body member. The front end of the clutch tube is provided with tapered spring fingers which are

55

adapted to engage the lead as the lead is held in the clutch and fed thereby.

Means is provided in the pencil for positively limiting the forward movement of the ejector during its ejecting action and also for positively limiting the forward movement of the clutch. Moreover, special means is also provided for retarding the retracted movement of the clutch after the lead has been ejected.

Further details of the invention will appear from the following description.

In the particular embodiment of the invention illustrated, the pencil comprises a barrel 20 in which there is rotatably mounted a body member 21 which forms a magazine, the body member being provided with a plurality of longitudinally extending grooves or channels 23 in its outer periphery for storing leads 22. A cap 24 is frictionally secured to the rear portion of the magazine or body member 21 and by rotating the cap 20 the magazine is also rotated.

As shown in Fig. 8, the magazine or body member 21 has secured therein a channeled tube 25. The tube 25 is freely rotatable in the member 21 with the exception of the rear end thereof which is slit at 27 opposite the channel 28 and is expanded sufficiently in the member 21 to provide a friction fit therein whereby rotation of the member 21 causes the tube 25 to rotate. This friction drive for the channel tube, clutch and ejector prevents damage to the pencil from overdrive.

A spiral tube 30 or a tube having a spiral slot therein is mounted in the body member and tube 25. The front end of the spiral tube 30 is secured in any suitable manner in a tapered sleeve 31 having a flange 32.

A tip 33 is secured in the front end of the barrel and has a rearwardly extending cylindrical portion 34 having inwardly extending slits 35. The tapered sleeve 31, as shown particularly in Fig. 4, is assembled by forcing the sleeve into the slotted rear end of the portion 34 of the tip, thus forcing this portion of the tip laterally into tight gripping engagement with the inner wall 36 of the forward end of the barrel 20. Thus the forward end of the tube 30 and the rear end of the tip 33 are effectively assembled in the forward end of the barrel.

The open rear end of the spiral tube 30 has mounted thereon a disk or washer 38 having a D-shaped opening 39 therein, as shown in Fig. 6. The washer engages the rear end of the magazine or body member 21 and the tube 30 is stretched between the fixed front end thereof which is disposed in the sleeve 31 and the rear end and the rear end of the tube is flared, as shown at 41. The disk or washer 38 is thus held in frictional engagement with the magazine or body member 21.

The clutch is illustrated particularly in Figs. 9 and 10 and comprises an elongated tube 45 having tapered or inwardly concaved fingers 46 at the front end thereof which engage and frictionally hold the lead which is fed by the clutch.

Between its ends the clutch tube 45 is provided with a laterally projecting lug 47. The clutch tube 45 has a longitudinally extending slot 48 and the rear end of the tube is slit transversely, as shown in Fig. 9 at 49, and the upper portion of the wall of the tube is bent inwardly, as shown at 50 and 51, these portions forming a stop 52 for limiting the rearward movement of the ejector. The ejector comprises a longitudinally extending elongated plunger 53 which is disposed in the clutch tube 45, a laterally bent portion 54 which

extends through the slot 48, and a rearwardly extending elongated portion 55 which, as shown in Figs. 1 and 2, extends into the channel 56 formed in the channel tube 25. This channel might, if desired, be formed in the inner wall of the body member or magazine 21. The ejector can be inserted through the slot 48 after the clutch tube has been completely fabricated and the lips have been folded inwardly.

Attention is called to the fact that the elongated end 55 of the plunger, by reason of its engagement in the channel 56, maintains the plunger 53 centered in the clutch tube 45. Moreover, attention is also called to the fact that the lug 47 does not extend through the spiral slot in the tube 30 into the channel 56. The clutch tube 53 is kept from rotating by reason of the portions 54 and 55 of the ejector engaging the walls of the slot 48 and the channel 56.

It will be noted from the showing in Fig. 2 that the bend 58 in the ejector engages the flange 32 to limit the operative or ejecting movement of the ejector. When the bend 58 engages the flange 32 the elongated end or tail 55 of the plunger rests on the outer surface of the spiral tube 30, thus preventing the ejector from being forced off center and against the inside of the clutch tube.

The forward movement or operative movement of the clutch is limited by means of a member interposed between the front end of the sleeve 31 and the tip 33. This member consists of an annular ring or sleeve 60 which is rotatably mounted in the portion 34 of the tip and is provided with a flange having tapered resilient fingers 61 which frictionally engage the outer surface of the clutch tube 45. As the clutch tube moves forward into the tip 33, the lug 47 will engage the flange and carry the ring 60 which has a limited axial movement forwardly into the tip until the portion 62 engages the inner surface of the tapered portion 63 of the tip 33. As the ejector and clutch are retracted, the clutch is retarded in its retractive movement by the fingers 61. During this retractive movement the ring 60 moves backwardly in the portion 34 of the tip until the rear edge thereof abuts against the front edge of the sleeve 31. The axial movement of the ring 60 is provided only to the extent necessary to insure free rotation of the ring.

The cap 24 may be of any desired construction but is preferably formed in the manner shown in Fig. 11 in which the cap as shown comprises a cap tube 70 having a tapered rear inner surface 71 adapted to receive a removable cap 72. One end of the cap 72 has secured therein an eraser 73. The disk 38 overlaps the rear ends of the storage grooves or channels 23, thereby retaining the leads 22 therein. However, when the cap is removed, the leads 23 can be lifted and then withdrawn longitudinally from the storage channels or grooves.

From the foregoing description it will be evident that a simple and practical mechanical pencil has been designed and that the pencil described is capable of accomplishing the objects set forth in the outset of the specification. As hereinbefore explained, positive limits for the forward movement of the ejector and clutch have been provided and these parts have been so designed as to provide a rugged construction in which the ejector is utilized to actuate the clutch during its operative and retractive movements.

The method of assembling the spiral and tip 75 to the barrel are simple, practical and effec-

tive and permit the assembling of these parts at a minimum cost.

Although one specific embodiment of the invention has been particularly shown and described, it will be understood that the invention is capable of modification and that changes in the construction and in the arrangement of the various co-operating parts may be made without departing from the spirit or scope of the invention, as expressed in the following claims.

What I claim is:

1. In a mechanical pencil, a barrel, a tip having its rear end secured in the front of the barrel, a spiral tube in the barrel, and means secured to the front end of the spiral tube for securing the tip in the barrel. 15

2. In a mechanical pencil, a barrel, a tip having its rear end secured in the front of the barrel, a spiral tube in the barrel, and tapered means secured to the front end of the spiral tube for securing the tip in the barrel. 20

3. In a mechanical pencil, a barrel, a tip having its rear end secured in the front of the barrel, a spiral tube in the barrel, and means secured to the front end of the spiral tube and disposed in the rear end of the tip for spreading the said end of the tip laterally and securing the tip in the barrel. 25

4. In a mechanical pencil, a barrel, a member rotatably mounted therein and having a longitudinal internal channel, a spiral tube mounted in said member, means securing the front end of said tube to the front end of the barrel, and means on the rear end of the tube frictionally engaging the member, said tube being held under tension between the front and rear ends thereof. 30

5. In a mechanical pencil, a barrel, a member rotatably mounted therein and having a longitudinal internal channel, a spiral tube mounted in said member, means securing the front end of said tube to the front end of the barrel, means on the rear end of the tube frictionally engaging the member, and means in said tube coacting with said spiral and channel to feed lead through the tube. 35

6. In a mechanical pencil, a barrel, a member rotatably mounted therein, a channeled tube mounted therein and having a friction fit adapted to permit relative rotational movement between the tube and member in which the tube is mounted, a spiral tube mounted in said first tube and fixed to the barrel, and lead feeding means in the spiral having means extending through the wall of the spiral tube into the channel whereby rotation of the member in the barrel will cause the lead to be fed through the spiral tube. 10

7. In a mechanical pencil, a barrel, a magazine member rotatably mounted in the barrel, a cap frictionally engaging the rear portion of the magazine member whereby rotation of the cap will rotate said magazine, a spiral tube in said magazine member fixed to the barrel, said magazine member having a longitudinal internal channel, and means in said spiral tube arranged to coact with the spiral and channel and feed the lead as the cap and magazine are rotated. 15

8. In a mechanical pencil, a barrel, a channeled member rotatable therein, a spiral tube in said member fixed to said barrel, a tip at the front end of the barrel, said tube having a spiral slot, a clutch in said tube having a lug extending into said spiral slot, and means for frictionally engaging said clutch and having a portion engageable by said lug to limit the forward movement of the clutch into the tip. 20

9. In a mechanical pencil, a barrel, a magazine therein rotatable in the barrel, a spiral tube in the magazine fixed to the barrel, and a disk on the rear end of the spiral tube held against rotation thereon and frictionally engaging the rear end of the magazine. 25

10. A clutch and ejector unit for a mechanical pencil comprising a clutch tube having an elongated slot adjacent the rear end thereof, the slot being closed at its ends, and an ejector comprising a plunger insertable through said slot, an angular portion extending through the slot, and an elongated portion outside the slot substantially parallel to the plunger in the tube. 30
